(57) **CLAIM**

The design for an infant carrier cover, as shown and described.

DESCRIPTION

FIG. 1 shows a side view of the infant carrier cover made in accordance with the principles of the present invention; FIG. 2 shows a front view of the infant carrier cover of FIG. 1;

FIG. 3 shows a rear view of the infant carrier cover; FIG. 4 shows a rear view of an infant carrier cover with the outermost cover pulled down;

FIG. 5 shows a side perspective view of the infant carrier cover open for inserting or removing an infant; FIG. 6 shows top view of the infant carrier cover;

FIG. 7 shows a front view of the infant carrier cover with the outmost layer folded down to show an infant disposed the cover; and,

FIG. 8 shows a side view of the infant carrier cover with the front outer layer and the rear outer layer folded down. The broken line showing of an infant carrier, in FIGS. 1-3, 5, 7, and 8, and the figure of an infant, in FIG. 7, is for illustrative purposes only and forms no part of the claimed design.
